UNITED STATES PATENT OFFICE.

CHARLES THOMPSON, OF ALLISON, IOWA.

CORN-PLANTER.

SPECIFICATION forming part of Letters Patent No. 312,931, dated February 24, 1885.

Application filed October 14, 1884. (No model.)

To all whom it may concern:

Be it known that I, CHARLES THOMPSON, a citizen of the United States, residing at Allison, in the county of Butler and State of Iowa, 5 have invented certain new and useful Improvements in Corn-Planters, of which the following is a specification.

The object of my invention is to produce a simple device, which may be attached to any 10 corn-planter, whereby the dropping of the corn may be performed automatically.

The invention consists in a cam provided with a flange, by which it is secured to the carrying-wheel of a planter by clips; a hinged 15 adjustable vibratory arm for conveying motion to the dropper-slide, with means for disengaging said arm from the cam, and for locking it when engaged; a horizontally and vertically adjustable pivot for said arm, and 20 a marker to indicate the location of the covered corn.

In the accompanying drawings, Figure 1 represents a side elevation of the invention attached to an ordinary corn-planter; Fig. 2, a 25 sectional plan view of the same; Fig. 3, a cross-section of the cam, covering-wheel, and their connections, in the line yz of Fig. 2; and Fig. 4, the vibratory arm and its attachments in detail.

Similar letters of reference indicate corresponding parts.

A is a cam-wheel consisting of two rings having two or more lateral offsets, and fastened at a uniform distance apart by stirrup-bolts D D, to the projecting lateral branches of 35 which they are secured by rivets or otherwise. To the other ends of the bolts is secured, by jam-nuts, a ring or flange, A', adapted to clear the hub of the carrying and covering wheel B and rest against the spokes, where it is fastened by suitable clips, a a.

In order to make the cam-wheel adjustable to any desired space laterally, these bolts are threaded a considerable distance from the end, so that by screwing up or unscrewing the nuts 45 the distance between the cam and the flange may be varied to suit the circumstances. This construction also admits of the cam being trued up with perfect accuracy after the flange-ring is attached to the wheel. The cam is designed 50 to be applied to any of the corn-planters in

ordinary use, and the adjustments are to meet the variations in the arrangement of different machines. A vibratory arm, C, connects the cam-wheel with the dropper-slide F. Under the rear end of this arm is a traveler, b, which follows the path between the sides of the cam as the latter revolves. The traveler is preferably placed over the vertical center of the cam, as shown. The arm is pivoted on a post, H, secured to a bracket, E. For convenience 60 of adjustment the post is threaded at the lower end, and passes through an eye in the outer end of the bolt E, which serves as a bracket and is similarly adjustable, both parts being fastened in position by jam-nuts. The bracket-bolt E passes through the side of the frame I, and the hole bored for it is the only one necessary in attaching the device to any planter.

To accommodate the arm to variations in the throw of the dropper-slide in different 70 planters, it is provided with a number of holes for the pivot, as shown. At the end opposite the cam the arm passes through a stirrup or staple, d, in the slide-bar F. By this means the corn is dropped automatically through the 75 medium of the carrying and covering wheels in their natural revolution, as will be readily seen.

To insure accuracy in the dropping of the corn at all times, the covering-wheel B is provided with markers e e, which leave an impression in the ground directly opposite the hill of corn. The marker is a plate projecting somewhat beyond the periphery of the wheel, as shown. By watching the relative position 85 of these impressions from time to time the operator is enabled to see that the rows are straight in both directions. Should the position of the markers with respect to the rows be changed in turning about, or otherwise, the 90 wheel is turned until the new impression aligns with the old.

As it is sometimes necessary to throw the dropper out of gear, the vibratory arm is hinged in a vertical plane between the pivot 95 and the cam, so that the traveler may be disengaged from the cam. A sleeve, f, slips over the joint and holds the arm rigid when in use.

I am aware that the automatic dropping of corn by means of a cam and a lever connect- 100

ing therewith and with the dropper-slide is not, broadly, new, and I do not claim such as my invention; but

What I do claim, and desire to secure by Letters Patent, is—

In a corn-planter, the cam A, adjustably connected with the flange or ring A' by stirrup-bolts D D, in combination with covering-wheel B, having markers e e, the jointed arm C, hav-

ing sleeve f, the adjustable pivot H and bracket E, and the slide-bar F, substantially as shown and described.

In testimony whereof I affix my signature in presence of two witnesses.

CHARLES THOMPSON.
